UNITED STATES PATENT OFFICE.

MARY A. PHILBIN, OF PITTSTON, PENNSYLVANIA.

DESIGN FOR A BURSE.

No. 38,089.

Specification for Design.

Patented June 19, 1906.

Application filed February 12, 1906. Serial No. 300,806. Term of patent 14 years.

To all whom it may concern:

Be it known that I, MARY A. PHILBIN, a citizen of the United States, residing at Pittston, in the county of Luzerne, State of Pennsylvania, have invented a new, original, and ornamental Design for a Burse, of which the following is a specification, reference being had to the accompanying drawings, forming part thereof.

Figure 1 is a front elevation of a burse, showing my design. Fig. 2 is a rear elevation of the same.

The burse is in the form of a lily, the upper front face of which is ornamented by ostensorium and dove, with the representation of angels kneeling at the base thereof, flowers,

bunches of grapes, and wheat-heads being arranged near the side edges of the burse. On the reverse side is a border of leaves, below which is disposed the Agnus Dei, to the left of which is a monogram composed of the letters in the name "Jesus," while to the right is disposed a monogram of the letters in the name "Mary."

I claim—

The ornamental design for a burse as shown and described.

MARY A. PHILBIN.
